INVENTOR:

W. S. Ireland,
by Knight & Cook, engrs.

UNITED STATES PATENT OFFICE.

WARD S. IRELAND, OF ST. LOUIS, MISSOURI, ASSIGNOR TO NATIONAL SHORTHAND MACHINE COMPANY, OF ST. LOUIS, MISSOURI, A CORPORATION OF DELAWARE.

SHORTHAND-MACHINE.

1,318,323.

Specification of Letters Patent.

Patented Oct. 7, 1919.

Application filed December 8, 1917. Serial No. 206,183.

To all whom it may concern:

Be it known that I, WARD S. IRELAND, a citizen of the United States of America, a resident of the city of St. Louis, in the State 5 of Missouri, have invented certain new and useful Improvements in Shorthand-Machines, of which the following is a full, clear, and exact description, reference being had to the accompanying drawings, forming 10 a part of this specification.

My invention relates to improvements in shorthand machines, and more particularly to certain combinations of elements associated directly with the key levers. The 15 main object of the invention is to provide a strong, simple and inexpensive means for supporting, guiding, alining and bracing or reinforcing the key levers. More specifically stated, an object is to produce a very 20 simple and highly efficient means for supporting and guiding simple and efficient printing elements which form part of very simple key levers, thereby simplifying the key controlled elements of the machine.

Figure I is a longitudinal section of a 25 shorthand machine constructed in accordance with my invention.

Fig. II is a plan view of the key lever guide.

Fig. III is a perspective view, partly in 30 section, illustrating one of the key levers, the key lever guide and the universal bar.

Fig. IV is a detail view of the paper feeding roll.

Fig. V is a side elevation, partly in 35 section, on the line V—V, Fig. IV, showing the universal bar and the paper feeding device.

Fig. VI is a section on line VI—VI, 40 Fig. V.

The strip of paper 1 passes from a supply roll 2, under a rod 3, thence upwardly and over a paper feeding roll 4, downwardly through an inclined passageway 5, and then rearwardly to a discharge opening at the 45 rear of the machine. Spools 6, located near the rear of the machine, support an inking ribbon 7, which travels under the type 8 on a type bar 9.

A designates key levers, each having a 50 long front lever arm 10 provided with a key 11, and a rear lever arm 12 which constitutes a printing hammer. Impression members 13 extend upwardly from the rear ends of the printing hammers 12 at points 55 below the type bar 9. All of the key levers

are arranged above and seated on a pivot rod 14, and the lower edge of each key lever has a recess 15 for the reception of said pivot rod. The key levers are thus loosely interlocked with and pivotally supported by 60 the rod 14. A retaining bar or stop bar 16, extending across the upper edges of the front lever arms 10, prevents the key levers from being accidentally lifted and disengaged from the pivot rod 14. Restoring 65 springs 17, seated upon the upper edges of the rear lever arms 12, force the key levers downwardly onto the pivot rod 14, at the same time forcing their rear portions onto a stop member 18 which lies below the im- 70 pression member 13. The springs 17 co-operate with the retaining bar 16 to prevent the key levers from being accidentally disengaged from, or released from, the pivot rod 14.

When a key is depressed, the lever to which it is secured turns about the axis of the pivot rod 14 and the impression member 13, at the rear of the lever, moves upwardly to force the strip of paper 1 and the 80 inking ribbon 7 toward the type 8, thereby printing one of the characters on the paper. The keys may be operated independently of each other to print individual characters, or several keys may be depressed simultaneously to print a combination of characters, as is well understood in this art. During 85 each key operation a universal bar 19 is actuated to transmit movement to a paper feeding device.

The universal bar 19 is seated upon the upper edges of the lever arms, or printing hammers 12, which extend rearwardly from the pivot 14. Arms 20 arranged at opposite sides of the printing hammers 12 connect 90 the universal bar 19 to the pivot rod 14. A feed arm 21, forming part of the universal bar structure, extends upwardly from one of the arms 20. 22 designates a restoring spring connected to the arm 21, as shown 100 in Fig. I. The universal bar 19 is located in front of and adjacent to the impression members 13, and the latter extend upwardly, preferably to a plane higher than the upper portion of the bar 19. The restoring spring 22 105 forces the universal bar 19 downwardly onto the upper edges of the printing hammers 12 in such a manner that it cooperates with the retaining bar 16 and springs 17 to retain the key levers in engagement with the 110

pivot rod 14. The universal bar is preferably connected to the pivot rod 14, as shown most clearly in Fig. III, but the key levers are merely seated upon said pivot rod. The 5 rear portions of the key levers lie between the universal bar 19 and pivot rod 14. It will be apparent that the simple key levers may be very easily and quickly applied to the universal bar and pivot rod, and when 10 arranged as herein shown all of these elements are securely fastened to the machine.

The key levers, including their printing hammers 12, which extend rearwardly from the pivot rod 14, are very firmly guided and 15 braced or reinforced by a key lever guide located near the rear of the machine. This guide comprises a base member 23, a series of comb teeth 24 extending upwardly from said base member at a point in front of the 20 pivot rod 14 and arranged between the front lever arms 10; a series of comb teeth 25 extending upwardly from the base member at the rear of pivot rod 14 and arranged between the printing hammers 12, and a 25 third series of comb teeth 26 which lie between the rear portions of the printing hammers 12. The rows of comb teeth 24 and 25 are separated from each other to receive the pivot rod 15, and these teeth very firmly 30 brace the loosely mounted key levers at points near the pivot rod 14. The printing hammers are positively alined and most effectively braced by the comb teeth 26 which lie near the impression members 13 at the 35 rear ends of said printing hammers. By bracing the printing hammers in this manner the entire key lever structure is held in the desired firm or rigid condition and all of the printing hammers are firmly held in 40 accurate alinement with the type.

The arms 20 of the universal bar are arranged in recesses 20', formed in the key lever guide to provide means for bracing and guiding the universal bar. The retaining bar 16, extending across the upper edges of the key levers, is preferably secured to the key lever guide as shown in Fig. III. The stop member 18, below the rear ends of the key levers, is preferably a pad secured 50 to the base 23.

The paper feeding means includes a feeding device arranged within one end of the feed roll 4, and a retaining device arranged in the other end to prevent retrograde movement. The upper end of the universal-bar arm 21 is notched to receive a pin 27 (Figs. IV and V) projecting from a drive member 28 in one end of the paper feeding roll 4. This drive member 28 is loosely mounted 55 in the roll 4 and it oscillates freely in response to movement of the universal bar. When the drive member moves in the direction indicated by the arrow in Fig. V, the small rollers 29 are firmly clamped in the tapering or wedge-shaped spaces between 60

said drive member 28 and the roll 4, and movement is then transmitted from the universal bar, through drive member 28 and rollers 29, to the feed roll 4. During the reverse movement, when the drive member 28 moves oppositely to the direction indicated by the arrow (Fig. V), the small rollers 29 are released and they do not transmit movement to the feed roll 4. The action is similar to the action of a ratchet and pawl. 75 The paper feeding roll 4 turns in the direction indicated by the arrow (Fig. V) in response to the oscillatory movements of the drive member 28.

To positively prevent retrograde movement, a stationary retaining member 28' (Figs. IV and VI) is arranged within the paper feeding roll 4, and secured to a stationary side frame 30 by a pin 31. Spring pressed rollers 29' are arranged in the 80 wedge-shaped spaces between the stationary retaining member 28' and the feed roll 4. These small rollers 29' allow the feed roll to turn freely in the direction indicated by the arrows (Figs. V and VI), but if an 85 effort is made to reverse the direction of movement, the small rollers 29', tending to roll toward the points of the wedge-shaped spaces, will coöperate with the stationary retaining member 28' to prevent such retrograde movement. 90

I claim:

1. In a shorthand machine, printing elements including key levers, a pivotal support for said key levers, each of said key levers having a front lever arm which extends forwardly from said pivotal support and a rear lever arm extending rearwardly from said pivotal support to constitute a printing hammer, each printing hammer 100 having an upwardly extending impression member near its rear end, comb-like guide members arranged between said key levers at points near the pivotal support, comb-like guide members arranged between said key levers at points near the upwardly extending impression members, a universal bar seated upon the upper edges of said printing hammers at points near their impression members and provided with a pair of arms 105 which extend forwardly to said pivotal support, and guide members fitted to the last mentioned arms.

2. In a shorthand machine, printing elements including pivotally mounted key 110 levers each having a front lever arm provided with a key and a rear lever arm constituting a printing hammer, each printing hammer having an upwardly extending impression member at its rear end, comb-like 115 guide members arranged between the printing hammers at points near their impression members and also at points near the pivotal support, a stop member arranged below and forming a seat for the rear ends of the 120 125 130

- printing hammers, a stop member arranged above and adapted to be engaged by the upper edges of the front lever arms, springs arranged above the printing hammers to 5 force the levers onto the stop members, and a universal bar seated upon the upper edges of said printing hammers at a point adjacent to and in front of their upwardly extending impression members.
- 10 3. In a shorthand machine, a pivot member, key levers arranged above said pivot member, the lower edge of each of said key levers being recessed to receive said pivot member and the face or wall of the recess 15 being seated upon said pivot member, each key lever comprising a front lever arm which extends forwardly from said pivot member and a rear lever arm extending rearwardly from said pivot member to constitute a printing hammer, comb-like guide members arranged between said key levers at points near their recesses, said comb-like guide members being separated from each other to receive said pivot member, and 20 comb-like guide members arranged between said key levers at points near the rear portions of their printing hammers.
- 25
4. In a shorthand machine, a pivot member, key levers arranged above said pivot member, the lower edge of each of said key levers being recessed to receive said pivot member and the face or wall of the recess being seated upon said pivot member, each key lever comprising a front lever arm which extends forwardly from said pivot member and a rear lever arm extending rearwardly from said pivot member to 30 constitute a printing hammer, comb-like guide members arranged between the front arms of the key levers at points near their recesses, said guide members between the front arms being separated from the guide members between the rear arms of the key levers at points near their recesses, said guide members between the front arms being separated from the guide members between the rear arms to provide a pivot receiving space wherein said pivot member is mounted, and comb-like guide members arranged between the key levers at points near the rear portions of their printing hammers. 35 40 45 50

In testimony that I claim the foregoing I hereunto affix my signature.

WARD S. IRELAND.
